FIG. 2

FIG. 4

UNITED STATES PATENT OFFICE.

WILLIAM P. McCORKINDALE, OF HOLYOKE, MASSACHUSETTS, ASSIGNOR TO MACCO MANUFACTURING CO., OF HOLYOKE, MASSACHUSETTS, A CORPORATION OF MASSACHUSETTS.

NAPKIN-DISPENSING DEVICE.

Application filed April 12, 1922. Serial No. 552,010.

This invention relates to improvements in napkin dispensing devices and its leading object is to provide a simple device which will dispense napkins through a delivery opening in the end wall of the container and in such manner that the napkins will be supported upon tapes attached to the propelling follower, so that the napkins will not offer any frictional resistance through direct contact with the follower guides.

With the above and other objects in view the invention comprises certain new and useful combinations, constructions and arrangements of parts, clearly described in the following specification and fully illustrated in the accompanying drawings, in which:—

Fig. 1 is a vertical sectional view through my improved device.

Fig. 2 is a front end view of the dispensing container.

Fig. 3 is a top plan view thereof.

Fig. 4 is a detail transverse sectional view of the dispensing container, showing the follower guides or tracks and the connection of the tapes therewith.

Fig. 5 is a detail transverse sectional view of the dispensing container illustrating a modified tape construction.

Fig. 6 is a detail sectional view of the modified tape construction on an enlarged scale.

Referring to the accompanying drawings illustrating the practical embodiment of my invention 5 designates a hollow standard, which rests upon a suitable base 6. This standard is provided with a head piece 7 to which the container case 8 is secured.

The bottom 9 of the case 8 is provided with a centrally located opening 8^a. Two follower guides or tracks 10 and 11 are mounted upon the base. The follower 12 is provided with a truck 13 which is equipped with two wheels 14 on one side which engage the rail or track 10 and is further equipped with two wheels 15 which engage the rail or track 11 on the other side of the truck 13. The wheels 14 and 15 are each grooved so as to straddle the track or rail engaged. The truck 13 carrying the wheels 14 and 15 is located rearwardly of the follower 12, which consists of a rigid plate, with a plane front face.

The follower is drawn across the rails or

tracks 10 and 11 by means of tapes 16 and 17, which are connected at their rear ends to the lower portion of the follower. These tapes engage the upper surfaces of the rails 10 and 11, and are adapted to be drawn over the rails by means of a weight 18, which is connected directly to a cable 19 which is pivotally connected to a rigid cross arm 20, the ends of which are connected to the ends of the tapes 16 and 17. The tapes 16 and 17 engage rollers 21 and 22, which are pivoted at the forward end of the case 8, near the front wall 23, which is provided with a relatively large delivery opening 24. The front wall 23 is provided with stops 23^a and 23^b, located at the opposite lower corners of the opening 24, so as to stop the movement of the napkins through the opening, under the pressure exerted by the weight upon the follower.

The pull of the weight is equalized upon the two tapes by means of the cross bar and the single cable or cord which connects this cross bar to the weight. The cable 19 engages a roller 25, supported for free rotation near the opening 8^a of the base 9. Each of the tapes is preferably provided with a series of metal casters or the like 27, which is adapted to provide anti-friction means capable of supporting the tape out of direct contact with the rail. In Fig. 6 I show a modified construction, wherein a series of rollers is provided on each tape. Referring to this figure the rollers are indicated at 27 as being supported upon the bracket or carrier 28, which is directly secured to the tape. Metal or steel tapes may be employed and small indentations stamped thereon, so as to minimize the area of contacting engagement with the rails.

The napkins 29 are arranged vertically in the case 8 with their lower edges resting on and supported by the tapes. Each napkin consists of a wide wing 29^a and a short wing 29^b, the short wings being adapted to form an initially grasped portion for the withdrawal from the case or container.

As the napkins are successively withdrawn through the delivery opening the weight will pull the follower toward the delivery opening and shift the napkins along the case, without any relative movement between the napkins and their supporting tapes, so that the napkins will not drag on the rails or

tracks and tend to pack against the follower or offer undue frictional resistance to the follower, propelled by the weight. The weight descends in the chamber of the hollow standard as the napkins are withdrawn.

Having described my invention, I claim:

1. A napkin dispensing device consisting of a case having a delivery opening in one end thereof and provided with horizontal guides leading to said opening, a follower movable on the guides toward the opening, stack supporting tapes connected to the follower and engaging the guides, guides for the tapes, and a means for maintaining a pull 15 upon the tapes to advance the follower toward the delivery opening.

2. A napkin dispensing device consisting of a case having a delivery opening in one end thereof, tracks located on the bottom of 20 the case and leading toward the delivery opening, a follower, wheels carried by the follower and engaging the tracks, stack supporting tapes connected to the follower and 25 engaging the tracks, and means for maintaining a constant pull upon the tapes to advance the follower toward the delivery opening.

3. A napkin dispensing device consisting of a case having a delivery opening in open end thereof, a follower horizontally movable 30 toward said delivery opening in said case, stack supporting tapes connected with said follower, means for maintaining a constant pull upon said tapes to advance the follower toward the delivery opening, and a series of 35 napkins supported on said tapes between the follower and the delivery opening and movable with said follower and tapes toward the delivery opening.

4. A napkin dispensing device consisting of a case having a delivery opening in one end thereof, a follower movable over the bottom of the case toward said opening, stack supporting tapes connected to said follower 40 to draw said follower toward the delivery opening, guides for said tapes, a cross bar connected to the ends of the tapes, a single cable connected to the cross bar, a guide for the cable, and a pendant weight connected 45 with the cable to maintain a constant pull 50 upon said tapes and follower.

Signed by me at Holyoke, Mass.

WILLIAM P. McCORKINDALE.
